UNITED STATES PATENT OFFICE.

ALFRED C. SLOATE, OF WYNNEWOOD, PENNSYLVANIA, AND JAMES C. WHYTE, OF WENONAH, NEW JERSEY, ASSIGNEES TO CONGOLEUM-NAIRN INC., OF PHILADELPHIA, PENNSYLVANIA, A CORPORATION OF NEW YORK.

DESIGN FOR A LINOLEUM FLOOR MAT.

Application filed June 23, 1927. Serial No. 22,537. Term of patent 7 years.

To all whom it may concern:

Be it known that we, ALFRED C. SLOATE and JAMES C. WHYTE, citizens of the United States, and residents of Wynnewood, Pennsylvania, and Wenonah, New Jersey, respectively, have invented a certain new, original, and ornamental Design for a Linoleum Floor Mat, of which the following is a specification, reference being had to the accompanying drawing, in which:—

Fig. 2 is an edge view.

We claim:

The ornamental design for a linoleum floor mat, substantially as shown.

ALFRED C. SLOATE.
JAMES C. WHYTE.
